UNITED STATES PATENT OFFICE.

ALDEN W. CHAMBERS, OF NEVADA, MISSOURI.

PLAITING APPARATUS.

SPECIFICATION forming part of Letters Patent No. 691,241, dated January 14, 1902.

Application filed April 20, 1901. Serial No. 56,768. (No model.)

To all whom it may concern:

Be it known that I, ALDEN W. CHAMBERS, a citizen of the United States of America, residing at Nevada, in the county of Vernon and State of Missouri, have invented certain new and useful Improvements in Plaiting and Crimping Boards, of which the following is a specification, reference being had therein to the accompanying drawings.

10 This invention relates to apparel apparatus, and particularly to that class known as "plaiting-boards."

The object of this invention is to provide novel means for plaiting and crimping material, and it is designed expressly for domestic or private use.

Furthermore, the object of the invention is to provide a plaiting-board in which the material and the plaiting-strips are held against 20 buckling when pressure is applied thereto or when in the act of ironing the surface for "setting" the material.

Furthermore, the object of the invention is to provide a novel form of frame whereby 25 the material after being operated upon may escape through a passage formed in one side of the frame and in the provision of a receptacle attached to the frame, into which the plaited material is discharged.

30 Furthermore, the object of the invention is to produce novel means for retaining the several parts in their proper positions and for affording access to either side of the frame.

With the above and other objects in view 35 the invention consists in the details of construction and the arrangement and combination of parts to be hereinafter more fully set forth and specifically claimed.

In describing the invention in detail reference will be had to the accompanying drawings, forming a part of this specification, wherein like characters denote corresponding parts in the several views, and in which—

Figure 1 is a plan view of a plaiting-board 45 and receptacle embodying the invention. Fig. 2 is a longitudinal sectional view thereof. Fig. 3 is a perspective view of a corner of a frame, illustrating the means for attaching the receptacle and the means of communication with the interior of the frame. Fig. 4 is a perspective view of a fragment of a combined plaiting and crimping strip. Fig. 5 is

a perspective view of a fragment of one of the retaining-bars.

In the drawings, 1 denotes the frame, which 55 is preferably formed of metal and made hollow and approximately square in cross-section, except that the rear side is composed of two rectangular tubes 2, separated by a channel or slot 3, through which the material 60 that has been acted upon in the crimping process may escape to the receptacle 4, said receptacle being here shown as cylindrical and having a slot registering with the slot 3 of the frame, as shown in Fig. 2. Each end of the 65 receptacle is provided with an arm 5, which fits in a socket 6, secured to the outer surface of the frame in any suitable manner, the said arm being an extension of a wire ring which is crimped on the end of the cylinder. 70

A guard 7 is adapted to embrace the rear section of the frame and to extend down to about the plane of the lower edge of the upper tube 2, and the inner depending portion of said guard has an extension 8, which reaches 75 down to a point slightly above the plane of the upper surface of the lower tube 2, there being sufficient space between its lower edge and the plane of the upper surface of the lower tube for the accommodation of the material which extends through the slot 3 in any direction. 80

The extension 8 is corrugated to conform with the corrugations of the plaiting and crimping strips, according to the effect which 85 is desired, it being understood that separate sets of crimping-strips may be employed, according to the result sought.

After the guard has been applied and the material and plaiting-strips have been alternately placed in position, as shown in the sectional view, the clamping-bar 10 is placed in the frame in contact with the outer strip or material, as the case may be, and said clamping-bar is provided with a metallic facing 11, 90 against which the binding-screws 12 are run to compress the material between the plaiting-strips. Top and bottom boards 13 are employed to form supports for the clamping-bar 10 and the plaiting-strips as the same are 100 compressed, said boards having ribs 14 extending over the edges of the frame in order to prevent displacement. The clamps 15 are also provided and embrace the frame in such

4,1,541

manner as to have their ends projecting in contact with the surfaces of the boards. After the material has been compressed, as just described, the top board is removed in order that access to the surface of the material may be acquired, and in order to prevent buckling of the plaiting-strips, by reason of the pressure exerted by the binding-screws, the retaining-bars 16 are employed, having their ends inserted through holes *a b*, formed in the guard and the wall of the frame, respectively, whereby the said end is anchored. The opposite end of each retaining-bar projects beyond the front edge of the frame and is engaged by a hook 18. The ends of the retaining-bar are flat, while the intermediate portion is provided with a rib 19, which rests on the upper surfaces of the plaiting-strips. These retaining-strips are used when the material is pressed, and it has been found in operation that a damp cloth should be placed over the surface of the material and a hot iron applied thereto, which will steam the material and heat the plaiting-strips, after which they will not spring out of position or buckle. The retaining-bar can then be removed and after placing a dry cloth, preferably cotton, over the goods the same should be pressed until the plaited material is dry. The top board should then be applied and the bottom board removed, so that the lower surface may be pressed in the manner just described. As soon as the material becomes cool after the pressing it can be removed from the plaiting-strips, and after applying the receptacle the finished goods can be passed thereto and the operation can then be repeated.

Having thus fully described the invention, what I claim as new, and desire to secure by Letters Patent, is—

1. In a plaiting-board, a frame, one side of the frame having a slot extending therethrough horizontally and a receptacle attached to the frame having an opening aligning with the slot to receive the material therefrom.

2. In a plaiting-board, a frame, one side of which is provided with a slot, a receptacle having arms fitting in sockets in the frame, said receptacles having an opening in alignment with the slot of the frame, substantially as described.

3. In a plaiting-board, a frame one side of which is provided with a slot, a receptacle having arms fitting in sockets in the frame, said receptacle having an opening in alignment with the slot of the frame, a guard secured to the frame and extending over and closing the slot thereof.

4. In a plaiting-board, a suitable frame one side of which is provided with a slot, a guard fitting on the side of the frame, said guard having a corrugated depending portion, as and for the purpose described.

5. In a plaiting-board, a frame, a guard secured thereto having a corrugated depending portion and corrugated plaiting-strips adapted to coat with the depending portion of the guard, for plaiting and crimping as described, a clamping-bar having a metallic facing, binding-screws threaded in the frame and acting in conjunction therewith.

6. In a plaiting-board, a frame having a slot on one side, a guard secured thereto for guarding the slot, corrugated plaiting-strips adapted to coat with the guard, and means for clamping the parts.

7. A plaiting-board, a hollow frame having a hole in one side, a receptacle attached to the frame and adapted to receive the material from the frame.

8. In a plaiting-board, a frame having a slot in one side, a receptacle secured to the frame to receive the crimped material, a guard for the slot, plaiting-strips and means for binding the parts together.

In testimony whereof I affix my signature in the presence of two witnesses.

ALDEN W. CHAMBERS.
